UNITED STATES PATENT OFFICE.

O. C. RICHARDSON, OF CHICAGO, ILLINOIS.

NECKTIE.

Application filed July 19, 1922. Serial No. 575,987.

This invention aims to provide a necktie which will hold its shape and be capable of being smoothed out readily, both the padding of the tie and the cover thereof being capable of independent yielding movement, thereby permitting the fullness to come into the tie at the required points, a drawing of the tie being avoided.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment shown can be made without departing from the spirit of the invention.

In the drawings:

Figure 1 shows in plan, a tie constructed in accordance with the invention; Figure 2 is a cross section on the line 2—2 of Figure 1; Figure 3 is a cross section on the line 3—3 of Figure 1; Figure 4 is a cross section on the line 4—4 of Figure 1; Figure 5 is a fragmental section showing the padding.

The tie forming the subject matter of this application comprises a padding denoted by the numeral 1 and comprising layers 2. The padding 1 may be fashioned from any suitable material which is not absolutely inelastic, the padding being capable of yielding and stretching somewhat, when the tie is tied. The constituent layers 2 of the padding 1 are united by a loose stitching 3, of any desired sort. The stitching at 3 may be a hand quilting stitch a machine quilting stitch, or any other stitch which will not destroy the elasticity of the padding.

The padding 1 is surrounded by a tubular cover 4, made of silk or any other material having some elasticity, the longitudinal edges of the cover 4 being overlapped as at 5 and being united by a blind stitching 6.

The stitching 6 may be of any desired kind which will not destroy the elasticity of the cover 4. If preferred such a stitching as that shown at 3 in Figure 5 may be used at the place marked by the numeral 6. The padding 1 preferably fills the cover 3 transversely, from one edge of the tie to the other. Intermediate its ends, the padding 1 is stitched to the cover 4, as shown at 7, the end portions of the padding being free, throughout the major portion of the length of the tie.

It will be noted that both the padding 1 and the cover 3 are so constructed that each can yield independently of the other. The result is that the cover 4 will not be distorted by the padding 1, the padding 1 on the other hand being free to yield and stretch as the cover yields and stretches. The fullness in the tie will always be found at the desired points, and the tie, as a whole, will never present a drawn or distorted appearance. Owing to the elasticity of the padding 1 and of the cover 3, secured by the stitching employed, the tie may be smoothed out, to remove creases, either by drawing the tie through the fingers, or by ironing the tie.

What is claimed is:

1. A necktie comprising a cover and a padding in the cover, the padding comprising layers united by an elastic stitching, the cover having overlapped edges united by another elastic stitching.

2. A necktie comprising a cover and a padding in the cover, the padding comprising layers united by an elastic stitching, the edges of the cover being overlapped and being united by another elastic stitching, and means for securing the intermediate portion of the padding to the intermediate portion of the cover, the ends of the padding being free throughout the major portion of the length of the tie.

In testimony that I claim the foregoing as my own, I have hereto affixed my signature.

O. C. RICHARDSON.
